AIR LIFT PUMPING MECHANISM

Filed July 12, 1921

Patented Sept. 21, 1926.

1,600,499

UNITED STATES PATENT OFFICE.

WADE H. WINEMAN, OF CHICAGO, ILLINOIS, ASSIGNOR TO SULLIVAN MACHINERY COMPANY, A CORPORATION OF MASSACHUSETTS.

AIR-LIFT-PUMPING MECHANISM.

Application filed July 12, 1921. Serial No. 484,201.

My invention relates to air lift pumping mechanism and more particularly to automatic controlling means for an air lift pumping system.

5 An object of my invention is to provide an improved air lift pumping system. Another object of my invention is to provide an improved air lift pumping system for use in deep wells whereby said system may 10 pump only as necessary to maintain the requisite water supply and may operate automatically to blow off any excessive head which may accumulate during the periods when said system is not in pumping operation. 15 Other objects of my invention will appear in the course of the following specification and appended claims.

In the accompanying drawings I have shown for purposes of illustration one embodiment which my invention may assume in practice.

In these drawings,—

Fig. 1 is a view mainly in elevation, but with parts shown in section, of the pumping system embodying the illustrative form of my invention.

Fig. 2 is a detail partially in central vertical section and partially in elevation of the float control means for the compressor.

30 Fig. 3 is a detail showing a portion of the control for the blow off valve.

Fig. 4 is another detail of this mechanism. It is a well known fact that it is possible in an air lift pumping system which is supplied with the discharge from a compressor to shut down the system during times when pumping action is not requisite, either by stopping the compressor entirely or by unloading the same. My invention relates to 40 the latter class of systems. It is also a well known fact that, in some wells, where the flow is fairly rapid, during periods when pumping is not going on, a head may accumulate to such a height that the foot piece 45 will be submerged so far that the available air pressure will not suffice to discharge air therefrom and so to enable the pump to start. In such cases, it is desirable to provide an auxiliary foot piece at a higher 50 point in the riser pipe whereby the head therein may be blown off to a sufficient extent to permit the starting of the pump. In such cases, it is not desirable to continue the operation of the auxiliary air lift pump any 55 longer than is necessary and my improved

mechanism comprises automatic means for controlling the operation of this auxiliary pump.

In the illustrative embodiment of my invention there is shown a compressor 1 having low and high pressure cylinders 2 and 3, respectively, connected by an intercooler 4 and discharging by way of a pipe 5 to a receiver 6. The compressor 1 is continuously driven by any suitable means, not shown. 60 The low pressure cylinder of the compressor is provided with an unloader of the intake type, which unloader comprises a casing 7 having a connection to the atmosphere at 8 and a connection to the compressor intake at 9, there being a valve 10 of well-known form arranged between the connections 8 and 9 and adapted when closed to prevent the passage of air from the passage 8 to the compressor intake and to effect the drawing of 70 a partial vacuum in the compressor intake whereby the work of compression is discontinued. The receiver 6 discharges by way of a pipe 11 to a down pipe 12 terminating in a foot piece 13 arranged in the riser 14, 80 which riser discharges by way of a pipe 15 to the tank 16 from which water may be drawn for use as desired by a pipe connection 17. For the purpose of regulating the operation of the compressor in such manner 85 as to cause water to be pumped to the tank 16 when the level therein falls below a predetermined desired amount and to discontinue the pumping operation when the water level has risen to a second predetermined 90 desired height, I have provided a valve mechanism generally indicated by 20 controlling a connection 18 from the receiver 6 to a piston 19 of well known form which controls the position of the intake control 95 valve 10. The mechanism 20 comprises a cylinder 21 having a bore 22 in which a valve 23 reciprocates under the control of means hereinafter described and this valve is operative to connect a pipe 24 with which the cylinder 19 is connected either to an orifice 25 which communicates with the pipe 18 or with an exhaust orifice 26, depending upon the position of the valve 23. The position of the valve 23 is controlled by a bell 100 crank 27 and the position of the bell crank is in turn controlled by a well known form of trigger mechanism adapted to be operated by a float 28 having a rod 29 connected thereto and stops 30 and 31 on the rod engageable 105 110

with an arm 32 for throwing the trigger mechanism. The reason for the provision of this trigger mechanism is the desirability of providing for means for sharply throwing the valve 23 to its opposite positions whereby it will be impossible for the compressor to become partially loaded and so interfere with the operation of the plant. It will be evident that when the water level in the tank 16 reaches the upper limit, the float 28 will rise and bring the stop 31 in contact with the arm 32, thereby throwing over the trigger mechanism in such manner as to raise the valve 23 and supply air to the mechanism 19 and thereby unload the compressor. When the water level has dropped to the desired degree the float 28 will cause the stop 30 to engage the rod 32 and thereupon the valve 23 will have its position sharply reversed and the compressor will be reloaded, the intake valve 10 being opened by springs 19' of well known construction. As explained above, it is quite possible that if for any reason but little water should be consumed from the tank 16 for a considerable period, the water level therein would not fall at all rapidly and accordingly, if the flow of the well in which the air lift pump previously described is disposed is rapid, the water level might rise to such height that the static head would be in excess of the pressure of the air in the foot piece 13. In order to permit the blowing off of this surplus head, I have arranged an auxiliary air lift pump as indicated at 34 in the riser pipe 14 and have placed it at such a height that it is capable of blowing off all head in excess of that which may be discharged by the foot piece 13. Air is supplied to this auxiliary air lift pump by way of a pipe 35 connected under the control of mechanism hereinafter described to the pipe 11 as indicated at 35'.

For the purpose of controlling the pipe 35 I have provided a valve casing 36 in which a valve 37 is mounted, which valve when open is adapted to permit the supply of pressure from the line 11 to the line 35 and when closed to interrupt this pressure supply. The valve 37 is provided with a stem 38 to which is secured a piston 39 and this piston is reciprocable in a cylinder 40. The cylinder 40 is connected by means of a T with a connection 41 leading to the compressor intake connection 9, and by a connection 42 to the relatively large tank 43 whose purpose will be shortly described. A valve mechanism, as indicated in Fig. 4, and comprising a casing 44 is arranged between the tee and the connection 9 and in this casing is a valve 45 which is adapted to be maintained in cracked position by a stop 46.

The operation of this mechanism will be readily apparent, it is thought, from the construction of the mechanism so far de-

scribed. When the compressor is unloaded by the closure of the intake valve 10, a vacuum is produced in the connection 9 and this vacuum operates to cause raising of the valve 45 from its seat and there is produced a partial vacuum in the tank 43. This vacuum likewise operates to reduce the pressure above the piston 39 whereby atmospheric pressure may raise the piston and so open the valve 37. The pressure accumulated in the receiver will then continue to discharge until it is no longer capable of discharging against the head existing in the well and thereafter the receiver will remain with a smaller pressure residue therein until the compressor starts up again due to the fall of level in the tank 16. This residual pressure will be sufficient to hold the unloader valve 10 closed. When the valve 10 is opened by the means previously described, on fall of water level in tank 16, the vacuum in the connection 9 will be broken and a gradual leakage of air, determined by the adjustment of the stop member 46, will begin to take place to the portions of the piping and to the tank 43 beyond the check valve 44. When the pressure builds up to a sufficiently high degree, gravity will cause the valve 37 to close and interrupt the discharge of air to the auxiliary air pump. It will be noted, however, that the capacity of the tank 43 may be so adjusted that the closure of the valve 37 will not occur until after the receiver has been pumped up to full pressure and until a time appreciably thereafter, whereby it will be evident that an ample period of operation of the auxiliary pump will be given for the blowing off of the surplus head. It will be understood that, by adjusting the stop member 46, the period during which the auxiliary air lift pump will operate may be adjusted as desired, and the adjustment of this member will be determined in proportion to the time which is required to blow off the static head which accumulates during the shut down periods of the well.

While I have in this application specifically described one form which my invention may assume in practice, it will be understood that this form of the same is shown for purposes of illustration, and that the invention may be modified and embodied in various other forms without departing from its spirit or the scope of the appended claims.

What I claim as new and desire to secure by Letters Patent is:

1. In an air lift system, air lift mechanism operable against a given head, a supplemental air lift mechanism for blowing off excessive heads, and vacuum controlled means for controlling said supplemental air lift mechanism.

2. In an air lift system, air lift mechanism operable against a given head, a sup-

plemental air lift mechanism for blowing off excessive heads, supply means for said air lift mechanisms simultaneously supplied with pumping fluid on initiating of pumping 5 operation, means receiving the discharge from said air lift mechanisms, and means for controlling the supply means for one of said mechanisms while the other mechanism is adapted to remain operative, said means being controlled by the liquid head in said discharge receiving means.

3. In an air lift system, air lift mechanism operable against a given head, a supplemental air lift mechanism for blowing off excessive heads, supply means for said air lift mechanisms, means receiving the discharge from said air lift mechanisms, and means automatically operative to simultaneously supply with fluid and to sequentially control the supply means for said mechanisms and controlled by the liquid head in said discharge receiving means.

4. In an air lift system, air lift mechanism operable against a given head, a supplemental air lift mechanism for blowing off excessive heads, a compressor supplying operating fluid separately to said air lift mechanisms, means receiving the discharge from said air lift mechanisms, and means controlling the operation of said compressor controlled by the liquid level in said discharge receiving means.

5. In an air lift system, air lift mechanism operable against a given head, a supplemental air lift mechanism for blowing off excessive heads, a compressor supplying operating fluid to said air lift mechanisms, means receiving the discharge from said air lift mechanisms, and fluid pressure 40 operated means controlling the operation of said compressor to control one of said mechanisms while the other remains operative and controlled by the liquid level in said discharge receiving means.

45 6. In an air lift system, air lift mechanism operable against a given head, a normally inoperative supplemental air lift mechanism for blowing off excessive heads, a compressor operative to supply said mechanisms with operating fluid, a tank to which said air lift mechanisms discharge, means controlled by the liquid level in said tank for controlling the loading and unloading of said compressor, and means rendered operative by the unloading of said compressor to cause said supplemental mechanism to operate on reloading of said compressor.

60 7. In an air lift system, air lift mechanism operable against a given head, a normally inoperative supplemental air lift mechanism for blowing off excessive heads, a compressor operative to supply said mechanisms with operating fluid, a tank to which said air lift mechanisms discharge, means controlled by the liquid level in said tank

for controlling the loading and unloading of said compressors, means rendered operative by the unloading of said compressor to cause said supplemental mechanism to operate on reloading of said compressor, and 70 means for varying the period during which said supplemental mechanism will be operative.

8. In an air lift system, main and auxiliary or starting air lift mechanisms, a compressor supplying pressure to said mechanisms, an intake unloaded for said compressor, a valve controlling the supply of fluid from said compressor to said starting air lift mechanism, and vacuum controlled 75 means for controlling said valve.

9. In an air lift system, main and auxiliary or starting air lift mechanisms, a compressor supplying pressure to said mechanisms, an intake unloader for said compressor, a valve controlling the supply of fluid from said compressor to said starting air lift mechanism, and means controlled by the vacuum produced in a chamber of said compressor when the latter is unloaded for controlling said valve.

10. In an air lift system, main and auxiliary or starting air lift mechanisms, a compressor supplying pressure to said mechanisms, an intake unloader for said compressor, a valve controlling the supply of fluid from said compressor to said starting air lift mechanism, means operative upon production of a vacuum in a chamber of said compressor to open said valve, and means 95 for preventing instantaneous closure thereof on destruction of said vacuum upon the reloading of said compressor.

11. In an air lift system, main and auxiliary or starting air lift mechanisms, a compressor supplying pressure to said mechanisms, an intake unloader for said compressor, a valve controlling the supply of fluid from said compressor to said starting air lift mechanism, means operative upon production of a vacuum in a chamber of said compressor to open said valve, and means 105 for preventing instantaneous closure thereof on destruction of said vacuum upon the reloading of said compressor, said means comprising a chamber communicable with said first mentioned means and chamber, and having a variable leak port communicating therewith.

12. In an air lift mechanism, main and auxiliary pumping units, a compressor, intake type unloading means therefor, a receiver, means connecting said receiver with each of said pumping units, means controlled by the discharge from said units for 120 controlling said unloading means, valve means controlling the connection between said receiver and said auxiliary pumping unit, a chamber communicating with the intake of the compressor beyond said unload- 125 130

ing means, a piston controlling said valve means and responsive to pressure conditions in said chamber, and a constantly cracked check valve in the line between said chamber and the compressor intake.

13. In an air lift mechanism, a riser pipe, a plurality of air discharge mechanisms arranged at different heights and adapted to cooperate with said riser pipe, branched 10 fluid supply means for conducting fluid to said air discharge mechanisms, and means in the branch to the higher one of the same to automatically interrupt flow therethrough, said means being independent in its operation of conditions in said riser pipe.

14. In an air lift mechanism, a main pump, a starting pump, means for respectively conducting fluid to said pumps, means for supplying fluid to both of said conducting 20 means simultaneously to start pumping, and automatic means for subsequently interrupting supply to said conducting means for the starting pump.

15. In an air lift system, air lift mechanism operable against a given head, a supplemental air lift mechanism for blowing off excessive heads, and means for controlling said supplemental air lift mechanism including a valve opened by the difference 30 between atmospheric pressure and a partial vacuum and closed by gravity.

16. In an air lift system, air lift mechanism operable against a given head, a supplemental air lift mechanism for blowing off excessive heads, and automatic controlling means for the latter wholly independent 35 of the degree of submergence of the former.

17. In an air lift system, an air lift pumping mechanism and fluid pressure supply means therefor including a compressor, 40 a supply line between said compressor and said mechanism, and a valve in said line controlled by the condition of said compressor.

45 18. A pumping system comprising pumping mechanism actuated entirely by fluid the pressure of which is above atmospheric pressure, a source of actuating pressure fluid therefor, and means for controlling the operation of said pumping mechanism including vacuum controlled mechanism adapted to control the supply fluid to said pumping mechanism.

55 19. In a pumping system, a fluid actuated pump, a compressor for supplying fluid thereto, and vacuum control means associated with said pumping mechanism to control the operation of said compressor.

60 20. In a pumping system, fluid actuated pumping mechanism actuated entirely by fluid the pressure of which is above atmospheric pressure, a compressor for supplying fluid thereto, and vacuum control means associated with said system to influence the de-

gree of pressure of the fluid pumped by said compressor and said pumping mechanism.

21. In a pumping system, fluid actuated pumping mechanism, a source of pressure fluid supply therefor, and control means for said pumping mechanism including a plurality of valves, each controlled by a vacuum.

22. In a pumping system, fluid actuated pumping mechanism, a source of pressure fluid supply therefor, and control means for said pumping mechanism including a plurality of valves made sequentially operable by a vacuum.

23. A system as set forth in claim 22 having means whereby said valves are relatively movable.

24. A pumping system comprising fluid actuated pumping mechanism, a source of pressure fluid supply therefor, and means for controlling the supply to said pumping mechanism including a plurality of valves adapted to be simultaneously subjected to a vacuum and thereafter to subject one of the same to a pressure greater than the pressure to which the remainder are subjected.

25. A pumping system comprising a main 90 and auxiliary pump, a receiver, and means adapted to allow said auxiliary pump to be operative while the receiver pressure is coming up to a pressure adapted to allow operation of said main pump.

26. A pumping system comprising an auxiliary and main pump, a source of pressure fluid supply therefor, and means whereby said source automatically has communication with the auxiliary pump when the pressure of said source is below the pressure adapted for a normal operation of said main pump.

27. A pumping system comprising an auxiliary and main pump, a source of pressure 105 fluid supply therefor, and means whereby said source automatically has communication with the auxiliary pump when the pressure of said source is below the pressure adapted for a normal operation of said main pump, 110 said means being controlled by the level of the liquid affected by the pumping operation.

28. A pumping system comprising an auxiliary and main pump, a source of pressure fluid supply therefor, means whereby said source automatically has communication with the auxiliary pump when the pressure of said source is below the pressure adapted for a normal operation of said main pump, 115 and means whereby said main and auxiliary pump are adapted to be operative by normal pressure at the source.

29. A pumping system comprising a main and auxiliary pump, fluid pressure supply 125 means therefor, and means whereby said auxiliary pump is automatically ready for operation when pumping by the main pump

- has reached the desired limit, but permitting said main pump to remain in communication with said supply.
30. In an air lift system, means for pumping a varying submergence head, and means having operative relation to the system for pumping a submergence head greater than normal substantially immediately after the pumping of a normal head ceases.
31. A pumping system comprising a main and auxiliary pump, a reservoir into which said pumps discharge, and means controlled by the liquid in said reservoir for controlling operation of said auxiliary pump independently of the main pump.
32. In an air lift pumping system, means for pumping a varying submergence head, and means for controlling the pumping of a head greater than normal including a plurality of receivers, a function of one being effective after a function of another has ceased to allow pumping of said greater head.
33. In an air lift pumping system, a main and auxiliary pump, means for controlling said auxiliary pump including a plurality of receivers, the function of one being effective after the function of the other has ceased, and vent means associated with one of said receivers to effect said sequence of operation.
34. An air lift pumping system comprising a main and auxiliary pump, and means whereby when discharge from said main pump has ceased said auxiliary pump prior to the time of discharging fluid therefrom is in operative relation to the system.
35. An air lift pumping system comprising a main and auxiliary pump, and means whereby when discharge from said main pump has ceased, said auxiliary pump prior to the time of discharging fluid therefrom is adapted to be operative independently of the level of the liquid in the well being pumped.
36. A pumping system comprising main and auxiliary pumps, and means whereby said auxiliary pump is adapted to be operative when the fluid supply therefor is under a pressure equal to or less than the normal pressure of the fluid for actuating the main pump.
37. An air lift system comprising pumping means adapted to discharge a varying submergence head and having continuously open discharge ports and means adapted to be operative to allow pumping of a head above normal when said pumping means is supplied with actuating fluid under a pressure equal to or less than the normal pressure.
38. An air lift system comprising a main and auxiliary pump, a compressor, and means whereby said compressor is adapted under normal operation to discharge a normal head by said main pump, and means whereby said auxiliary pump is adapted to be operative during an abnormal operation of said compressor.
39. An air lift system comprising a main and auxiliary pump, a compressor, and means whereby said compressor is adapted under normal operation to discharge a normal head as by said main pump, and means whereby said auxiliary pump is automatically operative during an abnormal operation of said compressor.
40. A pumping system comprising a main and auxiliary pump, a compressor for supplying actuating fluid thereto, fluid operated means for controlling said compressor, and means influenced by the liquid pumped by said auxiliary pump for affecting said fluid operated means.
41. In an air lift pumping system, means for pumping a normal head and an increased submergence head comprising a compressor, and means for automatically affecting the operating condition of said compressor to discharge said increased head.
42. In an air lift system, means for pumping a varying submergence head comprising a compressor, and means for automatically affecting the operation of said compressor to vary the amount of air compressed thereby upon the discharge of said head when above normal submergence.
43. In an air lift pumping system, means for pumping a liquid of varying submergence head comprising a compressor, and means for automatically affecting the operation of said compressor to vary the discharge pressure through said pumping means during discharge of a head greater than the normal.
44. In an air lift pumping system, pumping means, and means for allowing pumping of a varying submergence head including means for discharging a head above normal by increasing the pressure of the fluid pumped by said compressor over the pressure of the fluid pumped just previously to increasing said pressure.
45. In an air lift pumping system, pumping mechanism, means for allowing pumping of a varying submergence head including means for discharging a head above normal, said latter means automatically allowing increase of the pressure of the fluid pumped by said compressor over the pressure of the fluid pumped just previously to increasing said pressure.
46. In an air lift pumping system, pumping mechanism, and means for allowing pumping of a varying submergence head including means for discharging a head above normal by automatically increasing the pressure of the fluid pumped over the pressure of the fluid pumped just previously to increasing said pressure, said latter means including a valve which is urged towards

full opened position when increasing pressure of said fluid.

47. In an air lift pumping system, means for pumping a varying submergence head, 5 and means for automatically affecting the operation of said compressor to discharge a submergence head above normal, said means including a valve adapted to be actuated by fluid pressure having communication directly with said pumping means.

48. In an air lift pumping system, pumping mechanism, means for allowing pumping of a varying submergence head including means for discharging a head above normal 15 by automatically increasing the pressure of the fluid pumped by said compressor over the pressure of the fluid pumped just previously to increasing said pressure, said latter means including a valve adapted to be held open by fluid pressure during pumping of the head above normal.

49. In an air lift pumping system, means for pumping a varying submergence head, and means for automatically affecting the 25 operation of said compressor to discharge a head above normal, said means including

a valve adapted to be held open by fluid pressure during pumping of said head and during normal pumping.

50. In an air lift pumping system, means 30 for pumping a head above normal by automatically increasing the pressure of the fluid pumped by said compressor over the pressure of the fluid pumped just previously to increasing said pressure, said means including means adapted to control the flow of fluid which discharges the increased head.

51. In an air lift pumping system, means for pumping a varying submergence head including means for discharging a head 40 above normal by automatically increasing the pressure of the fluid pumped by said compressor over the pressure of the fluid pumped just previously to increasing said pressure, said latter means including a valve 45 to control flow of pumping fluid during pumping of the increased head and a receiver associated with said valve to control operation of the same.

In testimony whereof I affix my signature.

WADE H. WINEMAN.
